UNITED STATES PATENT OFFICE.

HENRY GRASSEY, OF GLEN ROCK, NEW JERSEY.

JIGGER.

Application filed November 5, 1927. Serial No. 231,177.

This invention relates to machines, such as jiggers, in which fabrics are passed back and forth around guiding means, as guides in a dye liquor vat, by winding the fabric up alternately on two beams, so that the passage is first in one direction and then in the other. Frequently creases will form in the winding thereof on either beam, this being due to the goods having some fullness between its selvages. The object of this invention is to provide effective but simple means for preventing this. Accordingly, I provide a fabric expanding bow which presents to the fabric a surface that is convex and which bow is slidable in a plane cutting the plane of travel of the fabric and is yieldingly held against the same. In the best form this bow is a part of a device having another such but reversely curved bow and arranged in a bend maintained in the fabric so that the bows bear against the two stretches thereof on opposite sides of said bend, the two bows being spaced further than such two stretches and each consequently yieldingly holding the other against the fabric. In this form of the invention it is not indispensable that the frame slide in a plane.

Fig. 1 of the accompanying drawing shows a jigger, partly in side elevation and partly in section on line 1—1 of Fig. 2, embodying the invention;

Fig. 2 is a horizontal section of the jigger on line 2—2. Fig. 1, with the device having the bows in plan and the superstructure omitted; and

Fig. 3 is a similar fragmentary view illustrating a modification falling within the scope of the invention.

1 is a dye-vat above which are journaled the horizontal and parallel beams 2 on which the winding of the fabric is reciprocally effected. The alternate driving of the two beams so as to cause the reciprocal winding thereon may be effected from a transverse shaft 3 having a pulley 4 to receive a belt (not shown) for rotating it constantly in one direction and having free to rotate thereon two bevel pinions 5 respectively in mesh with bevel pinions 6 on the two beams, these pinions 5 being also clutch members between which a clutch member 7, slidable to engage either and clear the other of the pinion clutch members, is splined on shaft 3, being adapted to be

shifted one way or the other by the fork 8. Any well-known bearing means 9 for the beams and shaft 3 may be employed. In the vat, near the bottom thereof and near the surface of the dye liquor, are shown the usual two pairs of guides, as rollers 10, around which, immersed in the liquor, the fabric A extends in a bend in its traverse from one beam to the other.

In Figs. 1 and 2 the hereinbefore mentioned device is a frame constructed and arranged as follows: 11 designates a pair of opposite parallel bars arranged one at one side and the other at the other side of and within the vat transversely of the axes of the beams and arranged to slide horizontally and lengthwise of themselves on studs 12 fixed in said sides of the vat, having longitudinal slots 11^a to receive said studs. Secured to each end of each bar at its inner side is a short strip 13, separated from the bar by spacers 14. The opposite strips 13, one on one bar and the other on the other, are rigidly connected by a curved bow 15. The connection between the bars 11, strips 13 and bows 15 may be effected by rivets or otherwise, so that they together constitute a rigid frame slidable on the studs 12 back and forth. The curvature of each bow 15 is outward from the other and in a plane extending transversely of the fabric. It will be seen that the frame, supported as stated, stands between the two upright stretches A' A² of the fabric, or in the bend thereof. In a horizontal plane cutting the frame the latter has from (at least) the crown or central part of one bow to that of the other a span greater than the span in the same horizontal plane between those two planes which the upright stretches of the fabric tend to assume between the upper pair of guides and the corresponding beam—in other words, with the frame present between such stretches its length is such as to maintain a bend in each stretch as shown in Fig. 1—and being curved in a plane extending transversely of the fabric it acts to bulge or belly them. In consequence, the fabric is extended transversely by the bows and winds on the receiving beam without creasing.

In the modification, Fig. 3, a bow 16 has its ends bent off parallel with each other and slotted, each such end receiving in its slot a pair of fixed studs 17 which guide the bow

for movement horizontally. Between a suitable fixed abutment 18 and each end of the bow is a compression spring 19 which normally holds the bow in the full-line position while permitting it to yield. In the example this bow slides on the studs in the same relation to the fabric as either of the bows 15.

When a bow is yieldingly held against the fabric it is found it prevents the formation of creases, which is not possible where the bow is rigid. This, broadly, is not new. But it is new to arrange the bow to slide in a plane cutting the plane of travel of the fabric. It is further new to provide a frame or other device arranged between and freely shiftable (whether or not in a plane) back and forth from one toward the other of the stretches on opposite sides of a bend therein and having a span exceeding that between said stretches and a convex surface curved in a plane extending transversely of the fabric and bearing against one of said stretches, whereby the other stretch will yieldingly maintain the device so bearing against the first-named stretch; one advantage of this is that, while the pressure of a convex surface is maintained against the fabric, the device may shift so as to accommodate itself to the change of positions which the two stretches A' and A² tend to undergo due to the diameter of the mass of fabric on the receiving beam increasing and that of the mass on the other beam decreasing as the transfer from the latter to the former proceeds.

Having thus fully described my invention, what I claim is:

1. In combination, with supporting means, means to draw a fabric lengthwise under tension first in one direction and then in the other comprising two beams on first one and then the other of which the fabric is adapted to be wound, means to maintain a bend in the fabric between the two beams, and a device arranged between, and freely shiftable on the supporting means back and forth from one toward the other of, the stretches of the fabric at opposite sides of said bend and maintaining a bend in each such stretch and also having the surface thereof in contact with one stretch curved in a plane extending transversely of the fabric. 45

2. In combination, with supporting means, means to draw a fabric lengthwise under tension first in one direction and then in the other comprising two beams on first one and then the other of which the fabric is adapted to be wound, means to maintain a bend in the fabric between the two beams, and a device arranged between, and freely shiftable on the supporting means back and forth from one toward the other of, the stretches of the fabric at opposite sides of said bend and maintaining a bend in each such stretch and also having the surfaces thereof in contact with said stretches each curved in a plane extending transversely of the fabric. 65

In testimony whereof I affix my signature.

HENRY GRASSEY.
